DESIGN FOR A BACK BAR

Joseph Moreno, Mountain View, Calif.

Application November 22, 1940, Serial No. 96,723

Term of patent 7 years

To all whom it may concern:

Be it known that I, Joseph Moreno, a citizen of the United States, residing at Mountain View, county of Santa Clara, in the State of California, have invented a new, original, and ornamental Design for a Back Bar, of which the following is a specification, reference being had to the accompanying drawing, forming a part thereof.

The figure is a front perspective view of the back bar, showing my new design.

The rear of the article is plain.

The dominant feature of the design resides in the portion shown in full lines.

I claim:

The ornamental design for a back bar, as shown and described.

JOSEPH MORENO.
